UNITED STATES PATENT OFFICE.

THOMAS MARSH, OF NORTH PROVIDENCE, RHODE ISLAND, ASSIGNOR TO HIMSELF AND HENRY F. JENKS, OF SAME PLACE.

IMPROVEMENT IN HOLDERS FOR SPINNING-RINGS.

Specification forming part of Letters Patent No. 118,544, dated August 29, 1871.

To all whom it may concern:

Be it known that I, THOMAS MARSH, of North Providence, in the county of Providence and State of Rhode Island, have invented certain new and useful Improvements in Spinning-Rings and Receivers, of which the following is a specification:

The nature of my invention consists in a compound ring-receiver, the one part of which is uncut and enters into the ring-rail and serves to hold the whole in position, the other part being cut radially, and also partly severed from the lower part by being cut horizontally, so that the upper part may be sprung open to admit of the reception, by the under-cut rabbet, of the edge of the ring. The object is to make a ring-receiver into and from which the ring may be placed or removed with little trouble and without necessitating the removal of the receiver from the rail.

Figure 1 represents, in perspective, one of my improved ring-receivers holding a ring, the rail being represented by dotted lines. Fig. 2 is a sectional view of the ring-receiver with the ring in position. Fig. 3 is a perspective view of the same. Fig. 4 is a plan, showing the ring and indicating the eccentricity of the flanges. Figs. 5 and 6 represent one form of a lever to be used in springing open the upper part of the receiver when it is desirable to insert or remove the ring.

Let the dotted lines at A, Fig. 1, represent a portion of the rail. The ring B, Figs. 2 and 3, is made as represented with the double flanges so that it may be reversed if desirable. The

ring-receiver D D¹ D² is in form as represented in the drawing, the upper part being cut radially at N. From the lower part of the cut N I make a horizontal cut, extending nearly around the receiver, as indicated by the lines e f e' f'.

From the above and an examination of the drawing it will be seen that the upper parts D¹ D² of the receiver may be sprung outward away from each other so as to enlarge the diameter of the rabbet k k, Fig. 2, thus freeing the ring B. The ring B is made with two flanges, each of which is eccentric, as shown in Fig. 4, by which arrangement the ring may be perfectly centered by simply turning it around in the receiver.

The separation of the upper parts D¹ D² of the receiver may be accomplished by either of the following methods: The ring-opener, Figs. 5 and 6, may be inserted and used as a lever to pry the sections apart, or it may be inserted as a wedge, the shoulders p p, Fig. 6, preventing it from being forced too far in and thus breaking the springing sections of the receiver. A third way is to insert the opener flatwise and then make a quarter turn.

I claim as my invention—

The ring-receiver D D¹ D² cut, as shown, and made with the springing members D¹ D², substantially as described, and for the purpose set forth.

In witness whereof I hereunto set my hand this 4th day of October, A. D. 1870.

Witnesses: THOMAS MARSH.
